INTERNAL COMBUSTION ENGINE

Filed Jan. 6, 1928

UNITED STATES PATENT OFFICE

2,085,943

INTERNAL COMBUSTION ENGINE

Jean A. H. Barkeij, Altadena, Calif.

Application January 6, 1928, Serial No. 244,864

1 Claim. (Cl. 123—76)

This application is a continuation in part of my application, Serial No. 157,845, filed December 29, 1926, now issued into Patent No. 1,874,419 under date of August 30, 1932.

5 This invention relates to engines and more particularly to engines of the sleeve valve type. In general, there are two types of sleeve valve engines commercially exploited, the double sleeve valve type and the single sleeve valve type employing a 10 single sleeve valve having an elliptical movement which results from the fact that the sleeve is moved with a combined reciprocating and oscillating motion, whereby any point on the sleeve traverses a closed elliptical path with respect to 15 the sleeve and cylinder axes. Both of these types of engines have given satisfactory service as compared with poppet valve engines but are however, relatively expensive to manufacture as compared with the standard poppet valve engine.

20 An object of this invention is to provide a sleeve valve engine that can be more economically manufactured.

Another object of this invention is to provide a 25 simplified sleeve valve engine construction embodying a single reciprocating sleeve having an approximate simple harmonic motion, said engine having exhaust ports adjacent the outer end of the cylinder and inlet ports adjacent the inner end of the cylinder.

30 Another object of this invention is to appreciably eliminate power losses due to carbon accumulations in the ports by providing a detachable cylinder head provided with horizontal extensions or bosses arranged to slide in the port recesses of 35 the single sleeve valve for removing any carbon deposits that tend to form therein.

Another object of this invention is to construct the inlet port or ports at the lower end of the sleeve and cylinder, but considerably above the 40 lowest position attained by the piston.

Still another object of this invention is to construct an additional air scavenging port in the cylinder at the lower or inner end thereof below the inlet port and above the lowest position attained by said piston.

Still another object of the invention is to introduce the fuel mixture and scavenging air into the cylinder under pressure, said pressure being induced by a blower of the positive impulse or centrifugal type in which the pressure produced is sufficient to answer the particular conditions and demands of the engine. Pressure producing means of the type in which pressure is produced by the action of a piston pump is not satisfactory 50 at times, since the speed of the piston pump means

is variable and furthermore it necessitates a complicated mechanism when employed with an engine of the multi-cylinder type.

A further object of the invention is to provide an improved piston construction for cooperative 5 action with the cylinder ports by providing a piston skirt adapted to cover up or mask the two rows of circumferential ports at the lower end of the cylinder during any position of the ports in the sleeve and the position of the piston in a four- 10 stroke cycle without increasing substantially the length of the connecting rod or the overall height of said engine.

A further object of the invention is to arrange 15 the ports circumferentially of the cylinder whereby to obtain a maximum port area and to facilitate the construction of common conduits for the inlet and scavenging ports respectively for a plurality of engine cylinders.

A further object of the invention is to provide 20 a construction in which mixing of the scavenging air and burnt gases is held to a minimum whereby to hold the burnt gas content trapped in the cylinder to a minimum for mixing with the following intake charge.

A still further object of this invention is to provide an engine construction in which the engine crankshaft is offset in such a direction that the decrease in piston pressure takes place on the side toward the sleeve-actuating eccentric shaft 30 almost perpendicularly above the driving point during the explosion stroke.

And a still further object of the invention is to introduce a fuel mixture charge at the lower end of the cylinder of an internal combustion engine 35 under more than atmospheric pressure by a rotative blower, the fuel being mixed with air at the blower intake whereby to eliminate the necessity of raising the pressure in the fuel jet relative to that of the blower at its outlet. Preferably the 40 valve is placed in front of the fuel introducing means in order to raise a greater sub-atmospheric pressure around said means than when said valve is placed between the inlet side of said blower and said mixing means.

In the accompanying figures illustrative of an embodiment of the invention like reference characters refer to like parts throughout the several views, and

Fig. 1 is a vertical sectional view of a typical 50 engine cylinder illustrating an engine of the sleeve valve type and particularly showing the porting arrangement, said view being taken substantially on the line 1—1 of Fig. 6.

Fig. 2 is a horizontal sectional view taken sub- 55

stantially on the line 2—2 of Fig. 1 showing one of the engine cylinders.

Fig. 3 is a horizontal sectional view taken substantially on the line 3—3 of Fig. 1 showing the 5 relation of engine parts when the piston is in its top position and the sleeve on its way upwards from its bottom position, the lower ports of said sleeve lying opposite the scavenging ports in the cylinder.

10 Fig. 4 is a graphical diagram illustrating the relative position of the upper and lower sleeve ports with respect to upper exhaust port and lower fuel mixture port of the cylinder during a complete engine cycle of four strokes in relation to the piston.

Fig. 5 is a similar graphical diagram illustrating the relative position of the piston upper edge, the sleeve lower edge with respect to the fuel mixture and an additional scavenging port 20 in relation to piston travel, and

25 Fig. 6 is a horizontal sectional view of a multi-cylinder engine showing the common inlet conduit and associated blower and in addition illustrates the relative positions of the sleeve and cylinder lower parts.

I have chosen for purposes of illustration to show my invention with a sleeve valve engine and have particularly illustrated an embodiment employing a single sleeve valve means of the 30 reciprocating type. In general, I have provided an engine A having a cylinder 10 suitably ported for intake and exhaust. More particularly, the cylinder is provided with an exhaust port means 11 adjacent the upper or outer end of the cylinder arranged to communicate with a suitable exhaust manifold structure 12. I have provided the cylinder with fuel mixture intake port means 13 located inwardly of the cylinder with respect to the cylinder exhaust port means and 40 below or inwardly of said cylinder intake port means I have provided an additional scavenging intake port means 14. The cylinder head B is secured to the engine block A by any suitable fastening devices such as bolts 15 and the cylinder head is preferably provided with a re-entrant portion 16 depending within the cylinder and carrying a combustion chamber 17. Preferably a spark plug 18 or other ignition device is carried by the cylinder head and is provided with suitable ignition points 18' located 45 within the combustion chamber. I preferably provide a junk ring 19 or other suitable sealing means adapted to be carried by the cylinder head and for engagement with the inner surface of 50 the sleeve valve means 20. The cylinder head depending portion is preferably spaced from the cylinder walls as at 21 to provide a pocket for accommodating the upper end of the sleeve valve means. The sleeve valve means is preferably 55 provided with exhaust port controlling means preferably consisting of recessed or slotted portions opening outwardly of the sleeve top edge, these recesses forming what I may term 60 sleeve exhaust ports 22, the lower edge of said ports being designated by the reference character 23 and the sleeve portions intermediate the ports forming extensions or fingers 24. The cylinder head is provided with bosses or lugs 65 25 bridging the sleeve pocket as shown in Figs. 1 and 2, these bosses or extensions being adapted to be straddled by the sleeve valve means in such a manner as to scrape or otherwise remove any carbon deposits that may accumulate or 70 75 form in the sleeve exhaust ports 22.

The sleeve valve means 20 is preferably actuated in such a manner as to be reciprocated axially of the cylinder 10. This movement is imparted to the sleeve valve means by means of an eccentric crank 26 by reason of the connecting device 27 which connects the arm 28 carried by the sleeve with the crank pin 29 carried by the crank 26. This crank is preferably operated or driven from the engine crankshaft by means of a chain drive 30.

10 A piston 31 is constructed for reciprocating operation within the sleeve valve means and is preferably connected with the crank 32 of the crankshaft 33 by means of a connecting rod 34. It will be noted that the operation of the sleeve 15 valve means is such, in this particular instance, that the same is operated preferably at one-half crankshaft speed.

The top face 35 of the piston is constructed as to closely approach the under surface of the 20 cylinder head when the piston approaches its outermost position of travel and said piston is arranged to move inwardly of the cylinder a distance sufficient to uncover the cylinder intake port means 13 and 14 when the same approaches 25 its innermost position of travel. The piston skirt 36 is preferably slotted at diametrically opposite points as at 36'.

30 The sleeve valve is provided with one or more intake port means adjacent the inner end of said sleeve valve means, and preferably said sleeve intake port means includes a plurality of ports disposed in a horizontal plane around the sleeve, that portion of the sleeve intermediate the ports providing a bridge 37 for connecting the sleeve portions above and below said ports. It will be noted that the slotted skirt portions 36' of the piston are arranged to be covered or masked by these bridge portions 37 of the sleeve 35 valve means. The outer and inner edges of these 40 sleeve ports *m* are respectively indicated by reference characters 7 and 8.

35 In Fig. 4, line 23 represents graphically the travel of the sleeve top edge relative to exhaust port 11 to illustrate the timing of exhaust opening and closing. Also, the top and lower edges of the sleeve intake port *m* are caused to travel relative to the intake port 13. Therefore, lines 7 and 8 represent the travel of these 45 port edges, while line 35 graphically represents 50 the travel of the piston top edge. Thus, it will be noted that the engine intake is open during a certain definite period when the sleeve intake port registers with the cylinder intake port and when said sleeve port is uncovered by the piston. 55 Fig. 5 adds to Fig. 4 the relation of the scavenging intake port 14 with respect to sleeve and piston travel, and it will be noted that said scavenging port 14 is closed by the sleeve valve when port 13 is open and is uncovered by said sleeve 60 valve only while the intake 13 is closed.

65 In Figs. 1 and 6 it will be noted that I have shown a blower or compressor structure C embodying a pair of blowers 38 and 38' driven by a drive shaft 39 connected with the engine crankshaft by suitable driving means 39'. These blowers are preferably arranged side by side on a common shaft and are preferably driven together. Suitable intakes 40 and 40' are respectively associated with these blowers 38 and 38' 70 and preferably have associated therewith the butterfly valves 41 and 41' respectively. If desired, a fuel nozzle 42 may be incorporated with one or both of these intakes. The blowers 38 and 38' each respectively include a blower casing 75

43 and 43' respectively having openings 44 and 44' communicating with the intake means 40 and 40'. Suitable blades 45 are associated within the casings of said blowers 38 and 38' respectively and said blowers are respectively provided with outlets 46 and 46' communicating respectively with the fuel mixture cylinder intake port means 13 and the cylinder scavenging intake port means 14. These blades are connected with shaft 39 driven by the engine and preferably are driven at various speeds depending upon the engine speed, that is, as the engine speed varies, the speed of the rotating blades will be correspondingly varied, these blowers being so constructed as to normally provide a pressure of approximately twice atmospheric pressure so as to prepare a compressed gas for introduction into the engine.

In most instances it is preferable to introduce fuel into the fuel mixture intake passage 13 intermediate the outlet 46 of the blower 38 and the cylinder. In Fig. 1 I have illustrated a preferred construction comprising a fuel nozzle 47 connected with the fuel supply or carburetor 48, this fuel introducing means being constructed so as to provide for fuel introduction in response to flow of compressed air past the nozzle 47.

In some instances the use of the air scavenging intake means is not necessary and I wish to have it understood that within the broad aspect of my invention I do not limit myself to the construction embodying both the fuel mixture intake as well as the pure air intake.

It will be also understood that the present construction is well adapted for use with engines of the compression ignition type in which pure air is admitted to the cylinder and the fuel is injected into the cylinder by a suitable fuel atomizing device or other means. Insofar as the broad aspects of my invention are concerned, it will be pointed out that the structure described in the appended claim is not limited to either specific type of engine.

The operation of the engine illustrated in Figs. 1 to 6 inclusive is graphically illustrated in Figs. 4 and 5 and the following description of the engine cycle will explain the engine operation.

Following the exhausting of the burnt gases through the exhaust ports the piston moves inwardly of the cylinder while the sleeve valve means is moving outwardly thereof. The exhaust ports 22 are moved into the sleeve pocket and the lower edge 23 of the sleeve exhaust port is moved past the upper edge 11^a of the cylinder exhaust port to effect a closing of the engine exhaust. The closing of the engine exhaust is designated at 50 in Figs. 4 and 5. Further movement of the piston inwardly of the cylinder creates a vacuum in the cylinder and the fuel mixture intake occurs at point 51 in Figs. 4 and 5, at which time it will be noticed that the sleeve intake port *m* has partially opened the cylinder intake port means 13. As the piston moves further inwardly of the cylinder, it will be noticed that the piston unmasks the sleeve intake port *m* and fuel mixture is introduced into the cylinder near its inner end under pressure due to the pressure built up by the blower or compressor. The closing of the engine intake is effected by the piston on its upward movement closing or masking the sleeve intake port *m*.

In my description and claim I have designated the end of the cylinder nearest the crankshaft as its inner end and the end of the cylinder most remote from the crankshaft as the outer end, and therefore motion of the piston inward-

ly and outwardly of the cylinder respectively defines a motion of the piston towards or away from the crankshaft. By inner and outer cylinder ports, I mean cylinder ports respectively located inwardly and outwardly of the cylinder relative to each other.

When engine intake closes, it will be noticed that the piston has travelled a considerable way outwardly of the cylinder from its innermost position of travel. If the cylinder was entirely 10 filled with fuel mixture when the piston is at the lowermost position of travel, this outward movement of the piston would compress the cylinder contents to about twice atmospheric pressure, or about 30 lbs. For this reason the compressor 15 is preferably designed to provide a pressure of about 30 lbs. to prevent the discharge of any of the fuel mixture from the cylinder during that portion of the time the intake port is open and the piston is travelling outwardly of the cylinder. It has been found, however, that the cylinder is not completely filled 100% when the piston is at its innermost position of travel.

The piston in cooperation with the blower or compressor builds up the pressure to approximately 30 lbs. when the engine intake closes. The wider the throttle is opened, the greater will be the initial volume when the piston is at its innermost position of travel and the speed of the engine and blower will, to some extent, determine the ultimate pressure obtained in the engine cylinder. I find that a blower or compressor of the positive impulse type or of the centrifugal type as herein illustrated are both able to produce a pressure of twice atmosphere at high 35 speeds. At the end of the compression stroke, it will be noticed that the sleeve exhausts port 22 is not in registration with the cylinder exhaust port and at the end of the power stroke, it will be noticed that the sleeve intake port is not in 40 registration with the fuel mixture cylinder intake port means 13.

In engines in which it is desired to employ a scavenging cylinder air intake port means 14, it will be noticed that the piston uncovers the 45 sleeve intake port near the end of the power stroke when the said sleeve intake port *m* is in registration with the cylinder port 14. It may be further noted that the engine intake of the scavenging air is controlled by piston movement 50 as the intake opening is controlled by the piston as well as the intake closing. It may be further noted that the exhaust port opens in advance of the opening of the scavenging air port. The initial opening of the exhaust provides for a rapid 55 reduction of the exhaust pressure in the cylinder previous to the introduction of the scavenging air, however, it will be noted that the scavenging air is introduced under a pressure built up by the blower or compressor and the burnt gases 60 remaining in the cylinder are very quickly swept out through the exhaust ports. In fact, by employing scavenging air pressure, the scavenging of the cylinder is quickly obtained and as a result there is practically pure air within the cylinder 65 prior to the following intake of a new combustible charge.

As shown in the preferred embodiment of my invention, I have provided a pair of blowers or compressors operatively driven together by the 70 engine, but in many instances I find that a single blower or compressor may be satisfactorily employed. In Fig. 7 I have provided a single blower 60 having an intake passage 61 which may be provided with a valve 62 and a fuel introducing 75

means 63 if so desired. The outlet of the blower communicates with the passage 64 which branches into a pair of separate conduits 65 and 66, the conduit 65 connecting with the cylinder intake port means 14' and the passage 66 connecting with the cylinder intake port means 13'. Preferably a fuel introduction device 67 is interposed in the passage 66 and includes a nozzle 68 through which the fuel is drawn by the flow of air through the passage 66. In this modified construction illustrated in Fig. 7, it will be noted that the cylinder intake port means 13' is a fuel mixture intake port similar to the intake port 13 illustrated in Fig. 1 and the intake port 14' is similar in function and construction to the intake port 14 shown in Fig. 1.

The crankshaft 33 shown in Fig. 1 is positioned to lie in the central longitudinal vertical plane of the engine but the crankshaft shown in Fig. 7 is offset from this central plane. This offset decreases the pressure due to the angularity of the connecting rod on that side of the sleeve where the unsymmetrical drive takes place. It is further preferred to rotate the eccentric crank 29 in a direction so that the upper surface of the eccentric crankshaft 26 rotates toward the sleeve. The result will be that during the explosion period the crank 29 of the shaft is more perpendicularly located below the point of resistance, thereby diminishing the stress exerted on the lug and the sleeve by the short connecting rod 27 connecting the crank with the extension 28 carried by said sleeve.

It will be noted that the intake port means carried by the sleeve is so constructed and operated as to control both of the cylinder intake port means.

The added application of a blower or compressor with an engine of the type herein illustrated has made it possible to employ a single

reciprocating sleeve in a practical manner, thereby eliminating the need of a second sleeve and other more complicated sleeve mechanisms which are subjected to an increased amount of wear. Furthermore, the blower has the advantage of breaking up the fuel to an extent impossible with an ordinary carburetor, such a construction being especially of importance where gasoline of a very high specific gravity is employed.

One or two blowers or compressors may be employed depending upon the volume of air needed in the engine. The throttle valves controlling the intake to the blowers may be operated simultaneously or separately.

It will be apparent to those skilled in the art to which my invention pertains that various modifications and changes may be made therein without departing from the spirit of my invention or from the scope of the appended claim.

What I claim as my invention is:

In a four-stroke cycle internal combustion engine, a cylinder having upper exhaust ports, inner intake ports including two rows of circumferential ports one row being located inwardly of the other, ported sleeve valve means controlling said cylinder ports and including a sleeve intake port operated to open said cylinder intake ports, said sleeve port opening the lowermost row of cylinder intake ports at the ends of the expansion stroke and the other row of cylinder intake ports at the end of the engine intake stroke, and a blower having an outlet communicating with said cylinder intake ports, said blower operatively driven by said engine, fuel injection means associated with said blower intake, and fuel injection means intermediate said blower outlet and said outer row of cylinder intake ports.

JEAN A. H. BARKELJ. 40
